CLAIM

We claim the ornamental design for a portable computer media station, as shown and described.

DESCRIPTION

FIG. 1 is a right side view of the design for the portable computer media station in accordance with the present design;

FIG. 2 is a top view of the design for the portable computer media station in accordance with the present design;

FIG. 3 is a left side view of the design for the portable computer media station in accordance with the present design;

FIG. 4 is a front view of the design for the portable computer media station in accordance with the present design;

FIG. 5 is a rear view of the design for the portable computer media station in accordance with the present design;

FIG. 6 is a perspective view of the design for the portable computer media station in accordance with the present design; and,

FIG. 7 is a perspective view of the design for the portable computer media station in conjunction with a portable computer in accordance with the present design.

In these drawings, the solid lines illustrate the claimed ornamental design, whereas the broken lines illustrate environmental features that form no part of the claimed ornamental design.
